CARBURETOR

Elmer Olson, Detroit, Mich., assignor to George
M. Holley and Earl Holley

Application October 22, 1938, Serial No. 236,526

2 Claims. (CL. 261—23)

The object of this invention is to provide a dual downdraft carburetor with a truly concentric float chamber. Additional objects are to provide such a carburetor with a common fuel orifice controlling the fuel for both mixing chambers; to prevent the fuel in the float chamber from overheating and to provide a low speed nozzle system in which the transfer from low speed operation to open throttle operation will be made smoothly and without any hesitation.

In the drawings:

Figure 1 shows diagrammatically the novel features of my invention.

Figure 2 shows a plan view of the complete carburetor taken on plane 2—2 of Figure 3.

Figure 3 shows a cross sectional elevation taken on plane 3—3 of Figure 2.

Figure 4 shows a cross sectional elevation taken on plane 4—4 of Figure 3.

In Figure 1, A is one of the main Venturi mixing chambers; B is a small rich mixture passage which discharges into the throat of the Venturi mixing chamber A; C is a fuel chamber supplied with fuel through a restriction D which communicates with the float chamber E, which is located in the air entrance F which completely surrounds it. The air chamber F supplies air to the Venturi mixing chamber A. The fuel chamber C communicates with the small rich mixture passage B through the passage G. These constitute the more essential elements of my invention. A corresponding rich mixture tube B₁ is shown discharging into the corresponding Venturi mixing chamber A₁.

In addition to the above elements, a low speed by-pass H is provided which projects into the opening G and removes from the rich mixture tube B the right mixture necessary for idling, which rich mixture is drawn along the horizontal passage J, which communicates with a fixed outlet K and an adjustable outlet L, both discharging adjacent to the upstream lip of the butterfly M in a well known manner. The air for atomizing the rich mixture in the passage B is drawn in through the small opening N.

Considering my invention as applied to a complete carburetor, the float chamber E in Figures 2, 3 and 4 is shown as containing the standard float mechanism O which maintains the fuel under substantially constant level just below the level of the two openings G and G₁. An air entrance P is provided in which is located an off center choke valve Q. This, of course, is no part of this invention, nor is the acceleration fuel pump, space for which is shown at R and U in

Figure 2, nor is the fuel economizer, space for which is shown at S and T. The float chamber is supported on a shoulder W which rests on a seat X.

5 In order to admit atmospheric pressure into the float chamber a passage V, Figure 3, is provided which acts as the float chamber vent.

Operation

When idling, fuel is picked up by the tube H and passed down through the low speed passage J to the low speed fuel outlet L. After the throttle opens a little fuel is also taken in through K and fuel continues to flow through K and L although the quantity is determined by the depression existing at the opening G, so that all the fuel at low speed is by-passed around the throttle. This explains why the danger of freezing is reduced by this construction.

15 As the throttle opens the fuel issues directly down the rich mixture passage being aspirated by air entering through the small opening N. The rich mixture in B is diluted by the main air flow through the venturi A.

20 With this combination, I have discovered that the following difficulties are either eliminated or minimized:

1. Fuel flow cutting out when turning corners;
2. Vapor lock in the fuel passages due to the air cooling of the float chamber;

25 3. Stalling during rapid deceleration.

With reference to difficulty No. 1, when turning a corner the driver of a car is not able to bank as the pilot does when turning in an airplane. The result is that the fuel level tilts and the fuel rises on one side of the float chamber and falls on the other, but with the construction shown the fuel level in the central chamber C within the float chamber E does not change appreciably. Hence the flow of fuel through the opening G and more particularly the flow of fuel up the passage H and down the passage J is not interrupted and remains substantially the same as when proceeding in a straight line.

30 45 With reference to difficulty No. 2, the air flowing around the float chamber keeps the temperature of the fuel in the float chamber E below the temperature at which there will be vaporlock.

With regard to difficulty No. 3, when releasing 50 the clutch and applying the brake, the fuel rushes forward because of the deceleration of the car. Again, the level of the fuel in the float chamber tilts, but the level in the central chamber C does not change appreciably.

55 All of these difficulties are minimized by the

relatively large size of the chamber C and by the location of the fuel and vapor outlet G. This chamber C and its outlet G are both concentrically located and the chamber C holds a substantial quantity of liquid. Applicant has discovered that by having a considerable volume of fuel between the point of restriction D and the fuel and vapor outlet G, the rate of discharge of fuel is not subjected to violent variations, when the car is accelerated, decelerated, or turned to go round a corner.

What I claim is:

1. In a dual carburetor of the drawndraft type, an air entrance, a constant level fuel supply chamber located substantially in the middle of the air entrance, two relatively large air and fuel mixing venturis located below said fuel supply chamber and symmetrically located therewith and communicating with said air entrance sur- 20

rounding said fuel supply chamber, two rich mixture passages located in the fuel supply chamber and oppositely inclined to each other so that the two passages pass each other as closely as possible, the zone in which said passages pass each other being the central zone of said fuel supply chamber, outlets from said rich mixture passages discharging into the throats of said venturis, and fuel well supply means located in said fuel supply chamber and connected to said inclined rich mixture passages, the points of fuel connection being substantially in the central zone of the fuel supply chamber.

2. A device as set forth in claim 1 in which there are two air entrances to the two inclined rich mixture passages and these air entrances are relatively small compared with the area of the discharge outlets from said rich mixture passages.

ELMER OLSON.
